DESIGN FOR A SMOKER'S STAND

Mauris De Meyere, Antwerp, Belgium

Application October 3, 1938, Serial No. 80,224

Term of patent 7 years

To all whom it may concern:

Be it known that I, Mauris De Meyere, a subject of the King of Belgium and a resident of Antwerp, Belgium, have invented a new, original, and ornamental Design for a Smoker's Stand, of which the following is a specification, reference being had to the accompanying drawing, forming a part thereof, in which

Fig. 1 is a side elevational view of the smoker's stand embodying my new design;

Fig. 2 is an end elevational view of the same; and

Fig. 3 is a top plan view thereof.

The design comprises a standard having a base and a slender central post, the latter supporting a sleeve which carries on one side an ash receiver and on the other side a table.

I claim:

The ornamental design for a smoker's stand, substantially as shown and described.

MAURIS DE MEYERE.
